UNITED STATES PATENT OFFICE.

ANDREW J. CZARNIECKI, OF PLYMOUTH, PENNSYLVANIA, ASSIGNOR OF ONE-HALF
TO FRANK ROMANCZUK, OF PLYMOUTH, PENNSYLVANIA.

MOTOR-SPRING HAIR CUTTER.

Application filed November 12, 1921. Serial No. 514,733.

To all whom it may concern:

Be it known that I, ANDREW J. CZARNIECKI, a citizen of the United States of America, residing at Plymouth, in the county of Luzerne and State of Pennsylvania, have invented certain new and useful Improvements in Motor-Spring Hair Cutters, of which the following is a specification.

10 This invention relates to certain new and useful improvements in hair clippers and has particular reference to the idea of providing a spring motor or other power means within the body of the clipper for operating 15 the cutting blades.

The primary object of the invention resides in the provision of a hair clipper wherein one of the blades of the clipper constitutes an integral part of the clipper body 20 or frame while a shiftable or reciprocating blade is operated by a spring motor contained within the body of the clipper.

A further object of the invention is to provide a spring motor operated hair clipper 25 wherein a band spring is associated with a relatively large gear for operating a pinion mounted upon a crank shaft, these in turn connected to a shiftable or reciprocating blade of the clipper.

30 The invention further embodies in a clipper including a spring motor for operation a reciprocating blade, a clipper body or casing having a removable cover to permit access to the interior mechanism of the clipper 35 for purposes of repairing or cleaning the same.

With the above general objects in view and others that will appear as the nature of the invention is better understood, the same consists of the novel form, combination and arrangement of parts hereinafter more fully described, shown in the accompanying drawings and claimed.

In the drawings, wherein like reference 45 characters designate corresponding parts throughout the several views,

Figure 1 is a top plan view of a hair clipper constructed in accordance with the present invention showing the hinged clips for retaining the cover in position on the clipper body,

Figure 2 is a side elevational view, partially broken away showing the spring driven gear meshing with the pinion supported on the crank shaft that in turn is con-

nected to the reciprocating blade of the clipper.

Figure 3 is a horizontal longitudinal sectional view taken on line III—III of Fig. 2 showing the connection between the driven 60 pinion supporting crank shaft and the shiftable cutting blade,

Figure 4 is a vertical longitudinal sectional view taken on line IV—IV of Fig. 1 showing the spring driven gear and the arbor 65 for placing the spring under tension,

Figure 5 is a horizontal longitudinal sectional view taken on line V—V of Fig. 4 showing the pawl and ratchet device associated with the arbor for placing the spring 70 under tension,

Figure 6 is a cross sectional view taken on line VI—VI of Fig. 1,

Figure 7 is a perspective view of the forward removable cover plate, and

Figure 8 is a fragmentary detail sectional view showing the stop device supported on the clipper body and associated with the spring driven gear.

Referring more in detail to the accompanying drawing there is illustrated a hair clipper comprising a body portion formed of a bottom wall 1 substantially circular as indicated in Fig. 5 and having a side extension 2 substantially rectangular in plan view 80 with the extreme forward end free of the bottom being upwardly inclined as shown in Figs. 2 and 4 with the terminal edge thereof formed with serrated cutting teeth 4. A side wall 5 formed integral with the bottom wall 1 has side extensions 6 merging into the upwardly inclined bottom wall extension 3, the portion of the side wall extensions 6 outwardly of the rectangular bottom wall portion 2 having inwardly directed 85 side flanges 7 shown more clearly in Figs. 1, 4 and 6. A removable cover plate 8 of a configuration similar to the bottom wall 1 is mounted upon the upper ends of the side walls and has a side extension 9 thereof terminating substantially above the point of connection between the bottom wall portion 2 and the inclined portion 3. A forward removable cover plate 10 having a depending 90 flange 11 upon the forward end thereof has the corners adjacent the extension cut away as at 12, shown more clearly in Figs. 1 and 7 supported on the flanges 7 with the forward ends of the flanges extending through the cut away portions 12 with the cover plate

providing an interlocking connection between the cover plate and clipper body. The cover 8 is maintained in position on the clipper body by hinge clips 13 having openings therein to receive lugs 14 carried by the cover 8.

A spring motor driven gear is arranged within the clipper body and is associated with the arbor 15 journaled in the bottom 1 and cover 8 as shown in Fig. 4, said arbor adjacent the lower end thereof having a ratchet wheel 16 secured thereto with a tensioned pawl 17 carried by the bottom wall 1 associated with the pawl as shown in Fig. 5. 15 The spring driven gear embodies a disk portion 18 rotatable upon the arbor 15 and supported upon the blocks 19 carried by the bottom wall, an upstanding annular flange 20 carried by the peripheral edge of the 20 disk being provided with external gear teeth 21. A band spring 22 coiled around the arbor 15 within the gear flange 20 has the inner end thereof secured as at 23 to the arbor while the outer end 24 is secured to the inner face of the gear flange 20.

A perpendicular crank shaft 25 is journaled at its opposite ends in the bottom wall 1 and cover 8 of the clipper body and has a pinion 26 fixed thereto in constant mesh 30 with the gear teeth 21. A shiftable clipper blade 27 having a serrated cutting edge 28 is flatly mounted upon the inclined portion 3 of the bottom wall and is pivotally supported upon the pin 29 adjacent the lower edge thereof, a link 30 being pivotally connected at one of its ends as at 31 to the upper side edge of the blade 27 while the other end thereof is connected to the crank portion of the shaft 25.

40 To place the spring 22 under tension, the thumb nut 32 removably secured to the upper end of the arbor 15 rotates the arbor, retrograde movement thereof being prevented by the pawl and ratchet 17 and 16 shown in Fig. 5. To hold the gear 18 stationary while placing the spring under tension, a strap 33 hinged as at 34 to the outer face of the side wall 5 carries a lug 35 upon its inner face adapted to project through an opening in the side wall for engagement with the teeth 21 of the gear, the spring being wound to the desired tension by rotation of the arbor 15. When it is desired to use the device for clipping hair, assuming that the spring is under tension as above described, the strap 33 is moved outwardly of the side wall 5 of the clipper body to disengage the lug 35 from the gear teeth 21, the spring ro-

tating the gear, and in turn the pinion 26 supported on the crank shaft 25. The link rod connection between the crank shaft and the blade 27 will cause a pivotal reciprocating movement of the blade to cause the teeth 28 to cooperate with the teeth 4 for cutting the hair projected between the cutting blades. 60 The forward cover plate section 10 may be removed to permit proper lubrication of the mechanism in the side extension of the clipper body while the body cover 8 may also be removed by releasing the clips 13 to 65 permit access to the band spring and gear wheel. The operation of the device is controlled by the hinge strap 33 carrying the lug 35 for engagement with the teeth 21 of the spring driven gear. 70

75 While there is herein shown and described the preferred form of the present invention it is nevertheless to be understood that minor changes may be made therein without departing from the spirit and scope thereof. 80

What is claimed as new is:—

85 A hair clipper of the type described comprising a substantially circular body portion, a side extension formed integrally therewith, the said extension being substantially rectangular in plan view with the forward free end of the body upwardly inclined, inwardly directed flanges carried by the side walls of said extension, a cutter blade formed integrally with the inclined bottom of the extension, a cutter blade pivotally supported on the said inclined bottom, upstanding blocks carried by the bottom wall of the body portion, an arbor journaled in said body portion, a gear journaled on said arbor and supported on said block, 90 a band spring associated with said gear and arbor, a crank shaft journaled in the casing, a pinion fixed to said crank shaft in mesh with said gear, a link rod connection between the crank shaft and the pivotally mounted cutting blade, a removable cover for said casing, securing means for said cover, said means embodying hinged clips carried by said casing, the said clips having slots formed therein and lugs carried by said cover adapted to engage the slots in said clips, and a forwardly removable cover plate carried by said extension, said plate having a depending flange carried by its outer edge, the said plate and flange having cutaway portions at their connecting edges which are adapted for engaging the inwardly directed flanges carried by the said extension. 100 105 110

In testimony whereof I affix my signature.
ANDREW J. CZARNIECKI.
